(57) **CLAIM**

The ornamental design for an industrial knife handle, as shown and described.

DESCRIPTION

FIG. 1 is a perspective view of an industrial knife handle embodying the design, according to the present invention; FIG. 2 is a front elevational view thereof;

FIG. 3 is a side elevational view thereof, the opposite side appearing as a mirror image thereof;

FIG. 4 is a top plan view thereof;

FIG. 5 is a rear elevational view thereof; and,

FIG. 6 is a bottom plan view thereof.

The broken lines shown in the Figures are for illustrative purposes only and form no part of the claimed design.
